UNITED STATES PATENT OFFICE.

GREGERS G. B. KJELGAARD, OF HOOSICK FALLS, NEW YORK.

SWIMMING APPARATUS.

Application filed May 12, 1923. Serial No. 638,632.

To all whom it may concern:

Be it known that GREGERS G. B. KJELGAARD says he is a subject of Denmark, who resides at Hoosick Falls, in the county of 5 Rensselaer and State of New York, has invented certain new and useful Improvements in Swimming Apparatus, of which the following is a specification.

This invention relates to swimming apparatus and is designed for aiding the 10 swimmer in propulsion of his body through the water.

Among the objects of my invention is the provision of a simple device, which may be 15 conveniently attached to the lower leg, and comprising in brief, a supporting means, an extensible and collapsible skirt, and means whereby the skirt may be alternatively extended and collapsed.

20 In the accompanying drawing, which illustrates detailed construction of the apparatus:

Fig. 1 is a front elevation of the supporting body attached to the leg with the skirt 25 removed.

Fig. 2 is a front elevation of the entire apparatus attached to the leg.

Fig. 3 is a front elevation of a modified form.

30 Fig. 4 is a front elevation of another modified form.

Referring now to the drawing Fig. 1 the leg attachment comprises a flexible support, in the form of a loose fitting sock or stocking 35 5 of suitable fabric enclosing foot and lower leg, the toe and heel being removed and the support being provided with a double row of eyelets 6, which permit the support to be laced firmly to leg, suitable lacing 40 7 being inserted in the eyelets and laced in the usual manner.

At regular intervals around the circumference of the support 5 are a plurality of pockets 8 sewed on. These serve for 45 the reception of a corresponding number of longitudinal, flexible stays 9 similar to corset stiffeners, said stays being firmly attached to the support 5, preferably by rivets.

Firmly secured, preferably by rivets, at 50 upper ends of stays 9 are flat metal springs 10, the lower ends of which are bent outward, and riveted or bolted to these lower ends are a corresponding number of longitudinal ribs 11 made of thin strips of wood, 55 rustproof metal or other suitable material.

Stitched around upper part of support 5

is a skirt 12 of rubbercloth, canvas or other suitable fabric; this skirt flares outwardly toward the lower margin and is reinforced by the ribs 11, these being inserted in 60 pockets sewed on the skirt and firmly attached by rivets 13 at their extremities.

Between the ribs 11 are attached additional longitudinal reinforcing stays 14 of 65 similar material as very fine corset stiffeners.

The lower edge of the skirt is turned inwardly and stitched over a cord 15, which serves to strengthen and hold the edges in 70 their proper shape.

At upper part of skirt 12 is made a slit 16, in which a triangular piece of fabric 17 is inserted, this allows upper part of skirt to spread, when foot is passed through in putting on or removing the apparatus. 75

In edges of slit 16 are attached eyelets 18, through which a lace 19 is inserted, this also passing through upper eyelets of support 5 and serves to draw upper part of support firmly around leg. 80

Around outer circumference of support 5 is a stitched on band 20, in which a number of eyelets 21 corresponding to the number of ribs are inserted. From these eyelets and to an intermediate part of ribs 11, 85 cords 22 are connected. These cords serve to limit the outward swinging movement of the skirt, when moved by the leg on the propulsion stroke, and thus prevent the skirt from turning inside out. 90

An elastic cord 23 interconnects the ribs adjacent their connection with the limiting cords 22 and serves to automatically collapse the skirt during walking.

As an alternative of attaching the ribs 95 11 to stays by small springs, I may employ an entire flat spring 24 Fig. 3, in which case additional limiting cords 25 may be added.

In alternative form illustrated in Fig. 4 I attach upper part of ribs 11 with upper 100 part of stays 9 by means of hinges 26 and employ flat, bent springs 27 attached to inside of ribs 11 to limit the inward movement of rib and skirt.

Having thus described my invention, 105 what I claim as new and desire to protect by Letters Patent is:—

1. A swimming apparatus comprising a supporting stocking, longitudinally reinforcing stays attached to said stocking, an 110 outwardly and downwardly flared skirt attached to upper portion of said stocking,

reinforcing ribs secured to said skirt and to upper ends of stays of stocking, and means for securing said apparatus upon the leg.

2. A swimming apparatus comprising a supporting stocking to be laced upon the leg, longitudinally reinforcing stays attached to said stocking, an outwardly and downwardly flared skirt attached to upper portion of said stocking, reinforcing ribs secured to said skirt and by springs attached to upper ends of stays of stocking, and cords from stocking to ribs of skirt.

3. A swimming apparatus comprising a supporting stocking to be laced upon the

leg, longitudinally reinforcing stays attached to said stocking, an outwardly and downwardly flared skirt attached to upper portion of said stocking, reinforcing ribs secured to said skirt and by springs attached to upper ends of stays of stocking, a longitudinal slit with an insert at upper part of said skirt, a non-elastic cord at lower margin of said skirt, an elastic cord for interconnecting the ribs of skirt, non-elastic cords from stocking to ribs of skirt, and means for closing slit in skirt and for fastening upper part of stocking around leg.

GREGERS G. B. KJELGAARD.
